Patented July 3, 1917.

UNITED STATES PATENT OFFICE.

THOMAS F. HAGERTY, DECEASED, LATE OF NEW YORK, N. Y., BY GEORGINA I.
HAGERTY, ADMINISTRATRIX, OF NEW YORK, N. Y.

STREET-CLEANING MACHINE.

1,232,294.

Specification of Letters Patent.

Patented July 3, 1917.

Application filed September 13, 1916. Serial No. 119,907.

To all whom it may concern:

Be it known that THOMAS F. HAGERTY, deceased, late a citizen of the United States of America, residing at New York, in the 5 county of New York and State of New York, did invent new and useful Improvements in Street-Cleaning Machines, of which the following is a specification.

This invention relates to street cleaning 10 machines, and it has particular reference to that class in which loosening and removal of the dirt from street surface is effected by means of a scraper.

The present invention has for its object 15 to produce a machine of simple and improved construction in which the frame that carries the scraper also supports a receptacle for the dirt, and means for transferring the dirt from the scraper to the receptacle.

20 A further object of the invention is to produce a simple and improved machine in which the frame that supports the scraper also carries a receptacle to receive the dirt, a movably supported scoop for transferring the dirt from the scraper to the receptacle and a specially constructed revoluble element for throwing the dirt from the scraper into the scoop, the latter being so supported that it may be retracted with respect to the 25 30 revoluble element so as to clear the same when it is tilted to transfer its contents to the receptacle.

Further objects of the invention are to 35 simplify and improve the construction and arrangement of the detailed parts of the device.

With these and other ends in view which will readily appear as the nature of the invention is better understood, the same consists in the improved construction and novel 40 arrangement and combination of parts which will be hereinafter fully described and particularly pointed out in the claims.

In the accompanying drawing has been 45 illustrated a simple and preferred form of the invention, it being, however, understood that no limitation is necessarily made to the precise structural details therein exhibited, but that changes, alterations and modifications 50 within the scope of the claims may be resorted to when desired.

In the drawing,—

Figure 1 is a vertical longitudinal sec-

tional view of a machine constructed in accordance with the invention, taken on the line 1—1 in Fig. 2.

Fig. 2 is a top plan view.

Fig. 3 is a detail view in elevation of a portion of the frame showing also the dirt receptacle and a portion of the scoop. 60

Fig. 4 is a detail plan view showing a portion of the scraper and related parts.

Fig. 5 is a fragmentary detail view of one of the bearings for the pushing element shaft. 65

Corresponding parts in the several figures are denoted by like characters of reference.

The wheel supported side members 15 of the frame are provided with spindles 16 on which the grounded wheels 17 are supported for rotation. At the forward ends of the frame members 15 the frame bars 18 are pivotally supported by pivot members 19, said forward ends of the frame members 15 being 70 preferably slightly upturned, as clearly seen in Figs. 1 and 3. The rearward ends of the frame members 15 have upturned brackets 20 which are connected together by a cross bar 21 on which the frame bars 18 are normally supported, said frame bars being, however, free to rock slightly about the pivot members 19, as indicated in dotted lines in Fig. 3, said rocking movement being limited by stop members, such as hooks 22 75 80 85 which by engagement with the projecting ends of the cross bar 21 will limit the rocking movement of the frame bars 18. The frame bars 18 at their upper rear ends are connected together by a handle bar 23; the lower front ends of the frame bars 18 are equipped with angular brackets 24 on which the scraper 25 is supported and secured by fastening members, such as rivets 26. The scraper 25 is preferably made of such a 90 95 length that it will project terminally beyond the side members of the frame, thus enabling it to scrape close to the curb.

The lower forward extremities of the frame bars 18 are formed or provided with upwardly extending brackets 27 affording bearings for a shaft 28 having a sprocket wheel 29 which is connected by a chain 30 with a sprocket wheel 31 which is associated with one of the ground wheels 17. The 100 105 shaft 28 carries a flat dirt pushing element

D which is revoluble therewith. Said dirt pushing element may be made in any convenient manner and of any material or combination of materials which will be suitable for the purpose which is to push the dirt loosened by the scraper in a rearward direction. A flat sheet of rubber, or a body of wood or metal edged with rubber, would be very suitable for the end in view; in the drawing, however, there has been shown a core 31 consisting of a flat piece of sheet metal upon which bristles or fibrous material, indicated at 32, is secured by wire stitching 33, the purpose, however, being simply to show a flat flexible or yieldable revoluble dirt pushing element, the free edges of which, as the shaft 28 revolves, will push the dirt rearwardly over the scraper 25, there being no intention for said element to contact with the surface of the street or to act as a dirt gathering sweeper. Bearing blocks 34 for the shaft 28 may be mounted for vertical adjustment on the brackets 27, as indicated in Fig. 5, for the purpose of enabling the dirt pushing element to be vertically adjusted so as to compensate for wear.

A dirt receptacle 35 of ample capacity is mounted on the cross bar 21 by means of ears or lugs 36 pivotally engaging said cross bar, said receptacle being capable of swinging in an upward and rearward direction so as to discharge its contents over the rear edge thereof into a can or other receptacle placed in the street or into some other convenient receptacle, not shown. The receptacle 35 may be supported in dirt receiving position by a cross bar 37 connecting the frame members 15 or in any other convenient manner. The frame members 15 are connected together near their front ends by a cross bar 38 on which are pivoted links 39 with which the top edge of a scoop 40 is pivotally connected, said scoop having a bottom member 41 which in practice is supported on the brackets 24 beneath the rearward portion of the scraper 25, said scraper being supported in a slightly tilted position so as to enable the front portion of the bottom member 41 of the scoop to be projected therebeneath, as clearly seen in Fig. 1. It will also be readily seen that the manner of supporting the scoop 40 on the links 39 will permit the scoop to be retracted from beneath the scraper so as to clear not only the scraper, but also the flat dirt pushing element when it is desired to tilt the scoop for the purpose of discharging its contents into the receptacle 35, as indicated in dotted lines in Fig. 1. For the purpose of convenience in manipulating the scoop is provided with a handle 42.

In the operation of this device the scoop is adjusted to the position shown in full lines in Fig. 1, and the machine is then

pushed over the surface of the street to be cleaned, the scraper serving to loosen and to gather the dirt which, by the rotation of the element D, is thrown back into the scoop. If the dirt is hard, frozen or otherwise caked, the operator by lifting on the handle 23, may rock the frame members 18 carrying the scraper so as to press or tension the latter with respect to the ground, thereby rendering its operation more effective and preventing it from sliding freely over the accumulated caked substance, and this will be accomplished, owing to the pivotal connection of the frame bars 18 with the frame members 15, without raising the wheels 17 from the ground and consequently without interrupting the operation of the revoluble element D. When a quantity of dirt has been gathered in the scoop 40, the operator by grasping the handle 42 may retract the scoop with respect to the scraper and the revoluble element until the upper edge of the scoop abuts on the front edge of the receptacle 35; the scoop may then be tilted, as seen in dotted lines in Fig. 1, to discharge its contents into the receptacle, after which it is restored to its initial position. The contents of the receptacle 35 may be discharged at stated intervals whenever desired by tilting said receptacle about the axis of the cross bar 21.

Having thus described the invention, what is claimed as new, is:—

1. In a machine of the class described, a pair of wheel supported frame members having upturned rear ends and a cross bar connecting the same, frame bars pivotally supported at the forward ends of the wheel supported frame members, a ground engaging scraper carried by the frame bars, and stop members connected with the frame bars to limit the rocking movement thereof with respect to the cross bar connecting the upturned rear ends of the wheel supported frame members.

2. In a machine of the class described, a pair of wheel supported frame members, an auxiliary rocking frame carrying a ground engaging scraper, means for limiting the rocking movement of the auxiliary frame, a dirt pushing element carried by the auxiliary frame and receiving motion from a wheel of the wheel supported frame, and a swingingly supported scoop adapted to receive the dirt loosened by the scraper.

3. In a machine of the class described, a pair of wheel supported frame members, an auxiliary rocking frame carrying a ground engaging scraper, means for limiting the rocking movement of the auxiliary frame, a dirt pushing element carried by the auxiliary frame and receiving motion from a wheel of the wheel supported frame, and a swingingly supported scoop adapted to receive the dirt loosened by the scraper, said

scoop having a bottom member, the front portion of which is insertible beneath the rearward portion of the scraper.

4. In a machine of the class described, a pair of wheel supported frame members, an auxiliary rocking frame carrying a ground engaging scraper, and a swingingly supported scoop adapted to receive the dirt loosened by the scraper, said scoop having a bottom member, the front portion of which is insertible beneath the rearward portion of the scraper.

5. In a machine of the class described, a pair of wheel supported frame members, an auxiliary rocking frame carrying a ground engaging scraper, and a swingingly supported scoop adapted to receive the dirt loosened by the scraper, said scoop having a bottom member, the front portion of which is insertible beneath the rearward portion of the scraper; in combination with means for conveying dirt loosened by the scraper over said scraper and into the scoop.

6. A pair of wheel supported frame bars, an auxiliary frame pivotally connected therewith, angular brackets carried at the lower forward portion of the auxiliary frame, a scraper secured on the angular brackets in a tilted position with its rearward portion raised with respect to the

brackets, pivotally supported links, and a scoop swingingly supported by said links, said scoop having a bottom portion adapted to rest on the angular brackets beneath the rearward portion of the scraper.

35

7. In a machine of the class described, a frame structure including wheel supported frame members, and auxiliary frame bars pivotally connected therewith, a cross bar connecting the wheel supported frame members at their rearward ends, a dirt receptacle pivoted on said cross bar, means for limiting the movement of the auxiliary frame bars with respect to said cross bar, a scraper carried by the auxiliary frame bars, said scraper being supported in a downwardly and forwardly tilted position, a dirt pushing element supported above the scraper for engagement therewith, links pivotally connected with the frame structure, and a scoop 40 45 50 swingingly supported by said links.

In testimony whereof, I affix my signature in the presence of two witnesses.

GEORGINA I. HAGERTY,
Administratrix of the estate of Thomas F.
Hagerty, deceased.
